(57) **CLAIM**

The ornamental design for a brake pad retaining spring and holder, as shown and described.

DESCRIPTION

This application contains subject matter related to co-pending U.S. application Ser. No. 12/371,336, entitled Brake Pad for a Disc Brake, filed on even date herewith.

FIG. 1 is a front, top perspective view from the right of a brake pad retaining spring and holder according to our novel design, the front, top perspective view from the left being mirror symmetrical;

FIG. 2 is a rear, top perspective view thereof from the right, the rear, top perspective view from the left being mirror symmetrical;

FIG. 3 is a front view thereof;

FIG. 4 is a rear view thereof;

FIG. 5 is a top view thereof; and,

FIG. 6 is a right side view, the left side view being mirror symmetrical.

The broken lines are for illustrative purposes only and form no part of the claimed design.
